TRUSSED BRAKE BEAM WITH FIXED HEAD

Frank W. Lewis, Chicago, Ill., assignor to Chicago Railway Equipment Company, Chicago, Ill., a corporation of Illinois

Application May 7, 1948, Serial No. 25,760

8 Claims. (Cl. 188—223.1)

1

The invention relates to railway brake beams of the truss type in which compression and tension members converge near the ends of the beam and mount end structures for carrying brake shoes.

In one familiar form of truss type of brake beam, commonly referred to as the A. A. R. Standard, the head is seated on the end of a channel-shaped compression member and a round rod tension member extends through the head and projects beyond the outer side of the head. A nut is threaded on the end of the tension member and bears against the outer side of the head, thus anchoring the end of the tension member to the end of the compression member. In such a beam, the neutral axis of the tension member intersects the neutral axis of the compression member outwardly of the center line of thrust of the head. At the inner side of the head, the tension member and compression member web are spaced apart transversely of the beam a substantial distance. The truss structure is effective beyond the center line of thrust of the brake head which arrangement is conducive to the resistance of the beam to deflection under load.

In another familiar type of brake beam, commonly referred to as the Huntoon type, the tension member of the beam engages the web of the channel-shaped compression member adjacent the inner side of the head and inwardly of the center line of thrust of the head. A securing device passes through the head and compression and tension members on the center line of thrust of the head. Since the tension member meets the compression member web substantially at the inner side of the head, the truss structure is not effective outwardly of the center line of the head and the ultimate strength of the Huntoon type of beam composed of members of the same cross sectional area as the members of an A. A. R. type of beam is substantially less than the A. A. R. type of beam. In the Huntoon type beam, when load is applied, the head may pivot rearwardly except for the resistance of the beam members to bending, whereas in the A. A. R. type beam, such pivoting is resisted by the end portion of the truss structure which corresponds to a beam having the depth of the truss at the point of application of the load and is greater than the combined thickness of the compression and tension members.

The main object of the present invention is to increase the strength of a Huntoon type brake beam by extending the effective truss to the end of the compression member and well beyond the

2

center line of thrust of the brake head substantially as in the A. A. R. Standard type beam.

Another object is to reinforce the truss structure by using a filler block to separate and oppose the beam members near the ends of the beam.

These and other detail objects as will appear below are attained by the structure illustrated in the accompanying drawings, in which:

Figure 1 is a top view of a brake beam embodying the invention.

Figure 2 is an end view of the beam drawn to an enlarged scale.

Figure 3 is a horizontal section through the end of the beam and taken approximately on the line 3—3 of Figure 2.

Figure 4 is a transverse vertical section taken approximately on the line 4—4 of Figure 3.

The brake beam includes a compression member 1 of channel-shaped cross section, a strap tension member 2 of rectangular cross section and of substantially the same height as the compression member, and a strut 3 intermediate the ends of the beam. The compression and tension members converge from the center of the beam towards each end of the beam and the tension member extends in a substantially straight line from the center of the beam to the extreme ends of the compression member and each end portion of the tension member extends rearwardly, as at 2a, around the associated outer edges of the compression member flanges 1a, and then inwardly, as at 2b, along the rear face of the compression member web 1b. Compression member 1, tension member 2 and strut 3 are positioned substantially in a horizontal plane.

A brake head 4 is mounted on each end of the beam and includes forwardly projecting lugs 5 for mounting a brake shoe 8 and may include an outer extension 6 for slidably mounting the beam from an adjacent bracket (not shown) on the truck framing. Extension 6 has a wear plate 7 riveted thereto. Brake head 4 has a recess 8 opening inwardly of the beam and receiving the end portions of the tension and compression members. Back wall 9 of recess 8 engages in-turned portion 2b of the tension member and the recess front wall has rearwardly extending webs 10 engaging the forward face of the tension member. The recess top and bottom walls 11, 12 engage the uppermost and lowermost faces of compression member flanges 1a. At the end of the beam, the adjacent portions of the compression and tension members are spaced apart a substantial distance transversely of the length

of the beam, thus deepening the truss structure where the head is mounted.

A filler block 13 is positioned between the end portions of the compression and tension members and includes vertical webs 14, 15, 16 extending between the compression member flanges 1a. Horizontal re-enforcing webs 17 are perpendicular to web 14. Webs 17 are offset at 17a and the offset portions are seated against the forward edges of flanges 1a facing the elongated rear face of the tension member. The front and rear edges of webs 17 are inclined to one another and are seated against the opposing rear face of tension member 2 and the front face of compression member web 1b, respectively. The filler block preferably is wedged between the tension and compression members adjacent their ends by driving the block lengthwise of the beam, thereby eliminating looseness between the members often encountered in built-up beams.

A vertically disposed rivet 18 maintains the beam members in assembly and extends through top and bottom walls 11, 12 of brake head recess 8, through flanges 1a of compression member 1, and through webs 17 of filler block 13.

This construction provides a substantially straight pull by the tension member from the center of the beam to each extreme end of the compression member and eliminates the tendency to straighten out the bend in the end portions of the tension member present in the older Huntoon type beam in which the tension member meets the compression member web adjacent the inner side of the head and then extends parallel with the compression member through the head.

The truss structure in the beam just described is effective to the outer end of the compression member and filler block 13 re-enforces the outer ends of the truss structure so that the ultimate load-carrying capacity of the beam is increased considerably over the ordinary Huntoon type.

The details of construction may be varied otherwise than as described without departing from the spirit of the invention and the exclusive use of those modifications coming within the scope of the claims is contemplated.

What is claimed is:

1. In a railway truss type brake beam, a channel-shaped compression member and a tension member with their adjacent end portions converging and interengaging, a brake head having a recess to receive the associated end portions, said tension member extending in a substantially straight line from the center of the beam to the extreme end of the compression member and being spaced from said compression member flanges at the inner side of said brake head, and a filler block received in said brake head recess and extending between said compression member flanges and seated against the forward edges of the compression member flanges and against the tension member.

2. In a railway truss type brake beam, a channel-shaped compression member and a tension member with their adjacent end portions converging transversely of the length of the beam, a brake head mounted on associated end portions, said compression member including a substantially vertical web and horizontal flanges extending transversely therefrom, said tension member end portion extending around the end of said compression member and along the rear face of the compression member web said members being spaced apart transversely of the length

of the beam at the inner side of said brake head, and a filler block extending between said compression member flanges and having offset portions seated against the forward edges of said compression member flanges and against said tension member.

3. In a railway truss type brake beam, a channel-shaped compression member and a tension member with their adjacent end portions converging, said tension member extending in a substantially straight line from the center of the beam to the extreme end of the compression member and the end portion of the tension member extending around the end of the compression member and along the rear face of its channel web, a filler block extending between the compression member flanges and having offset portions seated against the rear face of the tension member and against the opposing edges of the compression member flanges, a brake head having a recess receiving said member end portions and said filler block, and a fastening device extending through said brake head, compression member and filler block and maintaining assembly of said brake head and said members.

4. In a railway truss type brake beam, a compression member with a vertical web and horizontal flanges and a tension member with their adjacent end portions converging, said tension member extending in a substantially straight line from the center of the beam to the extreme end of the compression member and the end portion of the tension member extending around the end of the compression member and along the rear face of its channel web, a brake head having a recess receiving said member end portions, said tension member extending diagonally through the head, there being a filler block with converging sides engaging and spacing the tension member throughout the width of the head from the web of the compression member a distance at least as great as the width of the compression member flanges.

5. In a railway truss type brake beam, a compression member and a tension member spaced from one another transversely of the length of the beam throughout substantially the entire length of the compression member and with their adjacent end portions converging, the tension member extending around the end of the compression member, a wedge-shaped filler block between the forwardly and rearwardly facing portions of said members near their converging ends, a brake head having a recess opening inwardly of the beam and receiving the associated member end portions and filler block, and an element extending outwardly of the beam for slidably mounting the beam from the truck frame.

6. In a railway truss type brake beam, a compression member, a tension member inclined in substantially a straight line from the center of the beam to the extreme end of the compression member and extending around the outer edge of the compression member and inwardly along the rear face of the compression member, a filler block between the portions of said members spaced from the end of the beam and seated against opposing faces of the compression and tension members and holding them spaced apart transversely of the length of the beam, a brake head having a recess opening inwardly of the beam and receiving the associated member end portions and at least part of the filler block, and an element integral with and extending out-

wardly of the brake head for slidably mounting the beam from the truck frame.

7. In a railway truss type brake beam, a channel-shaped compression member with its flanges facing towards the front of the beam, a tension member, said members converging from the center of the beam towards each end, a brake head at each end of the beam having a recess receiving the end portions of said tension and compression members, a filler block positioned between the flanges of the compression member adjacent the inner side of the brake head and having offset portions seated against the forwardly facing edges of the flanges of the compression member and against the opposing rear face of the tension member and thereby holding the engaged portions of the compression and tension members spaced apart transversely of the length of the beam.

8. A brake beam as described in claim 7 which includes a holding element extending vertically through the compression member flanges and adjacent portions of the filler block to hold the block in position lengthwise of the beam.
